DESIGN FOR A SALT AND PEPPER DISPENSER

Frederick P. Hamrah, near Charlotte, N. C.

Application November 30, 1946, Serial No. 135,189

Term of patent 3½ years

(Cl. D44—22)

To all whom it may concern:

Be it known that I, Frederick P. Hamrah, a citizen of the United States, residing at near Charlotte, in the county of Mecklenburg and State of North Carolina, have invented a new, original, and ornamental Design for a Salt and Pepper Dispenser, of which the following is a specification, reference being had to the accompanying drawing, forming part thereof.

Figure 1 is a side elevation of the salt and pepper dispenser, showing my new design;

Figure 2 is a rear elevation, looking from the opposite direction from that in Figure 1;

Figure 3 is a bottom view;

Figure 4 is a top view.

I claim:

The ornamental design for a salt and pepper dispenser, substantially as shown.

FREDERICK P. HAMRAH.
